CLAIM

The ornamental design for an automotive body, as shown and described.

DESCRIPTION

FIG. 1 is a first perspective view from the front of an automotive body according to the design;

FIG. 2 is a second perspective view from the front of the automotive body according to the design;

FIG. 3 is a first perspective view from the rear of the automotive body according to the design;

FIG. 4 is a second perspective view from the rear of the automotive body according to the design;

FIG. 5 is a front view of the automotive body according to the design;

FIG. 6 is a rear view of the automotive body according to the design;

FIG. 7 is a side view of the automotive body according to the design;

FIG. 8 is another side view of the automotive body according to the design; and,

FIG. 9 is a top view of the automotive body according to the design.

The broken lines and areas enclosed by the broken lines are for the purpose of illustrating portions of the automotive body that form no part of the claimed design.

1 Claim, 9 Drawing Sheets
